UNITED STATES PATENT OFFICE

159,880

MILITARY EMBLEM OR SIMILAR ARTICLE

Elizabeth Will, Washington, D. C., assignor to the
United States of America as represented by the
Secretary of the Army

Application April 16, 1948, Serial No. 145,752

Term of patent 14 years

(Cl. D29—13)

To all whom it may concern:

Be it known that I, Elizabeth Will, a citizen of the United States and resident of the city of Washington, in the District of Columbia, have invented a new, original, and ornamental Design for a Military Emblem or Similar Article, of which the following is a specification, reference being had to the accompanying drawings, forming a part thereof.

Fig. 1 is a front view of a military emblem showing my new design.

Fig. 2 is a side view of the same.

It is understood that my design may be embodied in such articles as a badge, insignia, medal, medallion, plaque, or sign, without departing from the spirit of my invention.

I claim:

The ornamental design for a military emblem or similar article, as shown and described.

ELIZABETH WILL.
